(57) **CLAIM**

The ornamental design for a tee coupling, as shown and described.

DESCRIPTION

FIG. 1 is a perspective view of a first embodiment of our design for a tee coupling;

FIG. 2 is a left side view of the tee coupling shown in FIG. 1, the right side being shown in perspective in FIG. 1;

FIG. 3 is an end view of the tee coupling shown in FIG. 1, the opposite end view being identical;

FIG. 4 is a bottom view of the tee coupling shown in FIG. 1;

FIG. 5 is a top view of the tee coupling shown in FIG. 1; FIG. 6 is a perspective view of a second embodiment of our design for a tee coupling;

FIG. 7 is a left side view of the tee coupling shown in FIG. 6, the right side being shown in perspective in FIG. 6;

FIG. 8 is an end view of the tee coupling shown in FIG. 6, the opposite end view being identical;

FIG. 9 is a bottom view of the tee coupling shown in FIG. 6; and,

FIG. 10 is a top view of the tee coupling shown in FIG. 6. The broken lines in FIGS. 6, 8 and 10 are shown for illustrative purposes only and form no part of the claimed design.
